UNITED STATES PATENT OFFICE.

MORRIS S. MILLER, OF CLEVELAND, OHIO.

DESIGN FOR A HAND-STAMP.

55,137.

Specification for Design.

Patented May 11, 1920.

Application filed November 3, 1919. Serial No. 335,555. Term of patent 14 years.

To all whom it may concern:

Be it known that I, MORRIS S. MILLER, a citizen of the United States, residing at Cleveland, in the county of Cuyahoga and State of Ohio, have invented a new, original, and ornamental Design for a Hand-Stamp, of which the following is a specification, reference being had to the accompanying drawing, forming part thereof.

The figure is a perspective view of a hand-stamp, showing my new design.

I claim:

The ornamental design for a hand-stamp, as shown.

MORRIS S. MILLER.
